UNITED STATES PATENT OFFICE.

LOUIS T. WEISS, JR., OF NEW YORK, N. Y.

SELF-STARTING DEVICE FOR INTERNAL-COMBUSTION ENGINES.

1,023,903.

Specification of Letters Patent. Patented Apr. 23, 1912.

Application filed October 25, 1911. Serial No. 656,751.

To all whom it may concern:

Be it known that I, LOUIS T. WEISS, Jr., a citizen of the United States, residing in the borough of Brooklyn of the city of New York, Kings county, State of New York, have invented certain new and useful Improvements in Self-Starting Devices for Internal-Combustion Engines, of which the following is a specification, reference being had to the accompanying drawings, which form a part hereof.

It has been proposed heretofore to provide means for the introduction into the cylinder or into each cylinder of an internal combustion engine of a quantity of gas under pressure from some suitable source other than the usual carburetor, for the purpose of producing in such cylinder or cylinders an explosive mixture so that the engine can be started by the ignition of such explosive mixture before the engine operates on its own gas. Ordinarily such gas from an additional source of supply is admitted through the opening of a single valve and the quantity of gas admitted is therefore dependent upon conditions, such as the speed of movement of the valve, which may vary, so that the quantity of gas admitted is variable. This is very undesirable, not only on account of the uncertainty as to whether a proper explosive mixture will be formed, but also on account of the danger which may result, especially when, as is usual, the gas supplied is the acetylene gas from the storage tank.

It is the object of this invention to overcome these objections to the use of self-starting devices as ordinarily constructed and to make provision for the admission to the cylinder or to each cylinder of a predetermined quantity of gas at each operation of the starting device so that such operation shall be both certain and free from danger.

In accordance with the invention there are provided in the connection between the source of supply of the gas and the engine cylinders, two valves with a chamber of fixed volume between them, the valve adjacent to the supply being opened while the other remains closed, in order that the chamber may be filled with gas under pressure and then closed, while the valve nearer the cylinder is opened to permit the determined quantity of gas to flow into the cylinder after the other has been closed.

The invention will be more fully explained hereinafter with reference to its embodiment in a convenient and practical form as illustrated in the accompanying drawing in which—

Figure 1 is a view in side elevation showing a portion of an automobile engine equipped with the improved self-starting device. Fig. 2 is a detail view showing, on a larger scale the primary valve and one of the secondary valves shown in Fig. 1, the caps of the valve being removed. Fig. 3 is a view similar to Fig. 2 but showing the valves in different positions. Fig. 4 is a detail view in section through the primary valve.

The invention is illustrated in Fig. 1 of the drawing as applied to a 4-cylinder automobile engine, presumably of the usual 4-cycle type, but it will be obvious that the invention can be applied to a single cylinder engine or to an engine having any number of cylinders. The supply of gas for use in the self-starter is also indicated as derived from the usual cylinder of compressed acetylene gas employed for illuminating purposes, but it will also be obvious that the gas may be derived from any suitable source under a sufficient pressure to provide the quantity of gas requisite for the production of the explosive mixture in the cylinder or in each cylinder. It is also presumed that the gas is pure or air-free and that the quantity of air necessary to form the explosive mixture is that left in the cylinder or any one of the cylinders when the engine stopped.

In the embodiment of the invention shown in the drawing the gas under pressure in the tank *a* is permitted to pass therefrom through a cut-off cock *b* and, preferably, a pressure regulating device *c*, so that the gas may be supplied to the starting device under uniform pressure regardless of the diminishing pressure in the tank *a*, and a main delivery pipe *d*, to a primary valve *e* which, in any multi-cylinder engine, is also a distributing valve. From the valve *e* the gas is conducted through pipes, *f*, etc., which also form chambers of fixed volume, to cylinder or secondary valves *g*, *g*, etc., through which the gas is delivered to the corresponding cylinders *h*, *h*', etc.

The valves may be constructed in any suitable manner and may be operated by

any suitable means so that the primary valve shall be opened first to admit to the measuring chamber a definite quantity of gas and shall then be closed, and that the 5 secondary valve, or each secondary valve, which was closed during the opening of the primary valve, shall be opened after the primary valve closes for the purpose of admitting the gas from the measuring chamber to the cylinder. It will be understood 10 that the secondary valve is a necessity in order to prevent the waste of gas as well as to insure the admission of a measured quantity of gas to the cylinder regardless 15 of the condition of the exhaust valve or port of the cylinder, even in a single cylinder engine, and that it is especially desirable in a multi-cylinder engine because, without undue waste of gas and regardless of the interior 20 conditions of the other cylinder or cylinders, it assures the introduction into one of the cylinders of the proper quantity of gas for the production therein, with the air already contained therein, of a proper 25 explosive mixture.

In the construction shown in the drawing the main supply pipe d is shown as connected at d' to the valve casing e' which is provided internally with channels e^2 controlled by a valve disk e^3 having ports e^4 . The valve cap e^5 is provided with ports e^6 to which are connected the several pipes f , f' , etc., through which the gas is conducted to the secondary valves. The stem e^7 of the 30 valves has secured thereto an arm i which is connected to an operating rod i' . This is shown as extended through the dash k of the automobile and as connected to a lever i^2 which may be operated either by the hand 35 or by the foot, and as acted upon by a spring i^3 to maintain all the valves normally in closed position.

Each secondary valve g may have a construction substantially similar to that of the 40 primary valve, comprising a disk valve g' having a single port g^2 to control the passage of gas from the pipes f , f' , etc., through a passage g^3 in the valve body g^4 to the corresponding cylinders h , h' , etc. The stem 45 g^5 of the valve has secured thereto an arm i^4 which is connected to the operating rod i' so that, for convenience, both the primary valve and the secondary valve may be operated by a single movement of the hand or 50 foot.

As clearly indicated in the drawing, all the valves are closed normally and when it is desired to use the self-starting device, the hand or foot is applied to the lever i^2 so as 55 to move it in a forward direction against the spring i^3 . All the valves are moved together, but the ports of the primary valve and each secondary valve are so related, as clearly shown in Figs. 2 and 3, that during 60 the first part of the movement the ports of

the primary valve are opened while the port of each secondary valve remains closed, and that in the continued movement of the actuating means the ports of the primary valve are closed and then the port of each secondary valve is open. When the primary valve is opened the gas from the source of supply is admitted to the chambers formed by the pipes between the primary valve and the secondary valves, filling such chambers at a 70 pressure determined by the pressure in the tank a or by the regulating valve c . When the primary valve is closed and the secondary valves are opened the gas in the pipe chambers flows into the cylinders, supplying to each cylinder a determined volume of gas under a determined pressure. It will be observed that by the closing of the primary valve, communication from one cylinder to another is cut off so that the quantity of gas admitted to any cylinder is not affected by the conditions in any other cylinder. The primary valve is opened during the return movement of the actuating means, but the effect of this opening is only to recharge the 75 pipe chambers between the primary and the secondary valves. The effect of the forward movement of the actuating means is therefore to build up the pressure in the pipe chambers to the predetermined degree in 80 case it has fallen since the last previous use of the starting device.

It will be obvious that the form and arrangement of the valves may be varied to suit different conditions of use and that the invention is not limited to the particular construction and arrangement shown and described herein.

I claim as my invention:—

1. A self-starting device for an internal combustion engine having a plurality of cylinders comprising a source of supply of gas under pressure, a primary distributing valve connected to the source of supply, separate connections from said primary distributing valve to each of the cylinders, a secondary valve included in each of said separate connections with a gas chamber interposed between the primary distributing valve and each secondary valve and means to actuate 100 said valves whereby the primary valve is opened and closed while the secondary valves are closed and the secondary valves are opened while the primary valve is closed.

2. A self-starting device for an internal combustion engine having a plurality of cylinders comprising a source of supply of gas under pressure, a primary distributing valve connected to said source of supply, separate connections from said primary distributing valve to the several cylinders, a secondary valve included in each of said separate connections with a gas chamber interposed between the primary distributing valve and each of said secondary valves and a com- 105 110 115 120 125 130

mon actuating means connected to all of
said valves, said valves having their ports
so disposed that the primary distributing
valve is opened and closed while the second-
ary valves are closed and the secondary
valves are opened while the primary dis-
tributing valve is closed.

This specification signed and witnessed
this 24th day of October, A. D., 1911.
